Specification for Design.

Patented Dec. 13, 1921.

Application filed April 28, 1921. Serial No. 465,222. Term of patent 14 years.

To all whom it may concern:

Be it known that I, SAM SWANSON, a citizen of the United States, residing at Rockford, in the county of Winnebago and State of Illinois, have invented a new, original, and ornamental Design for a Stocking, of which the following is a specification, reference being had to the accompanying drawing, forming a part thereof:

In the drawing,—

Figure 1 is a rear view of a fashioned stocking embodying my new design, showing the stocking as it appears on a leg model, the lines making up the design diagrammatically representing rows of drop stitches;

Fig. 2, a side view of the stocking on the model;

Fig. 3, a diagrammatic enlarged view illustrating a portion of the design which is effected by the drop stitch; and

Fig. 4, a flat view of the stocking showing the design as it appears when the stocking is removed from the form.

In Figs. 1 and 2, the lines illustrating the ornamental design, represent an effect produced by drop stitches.

I claim:

The ornamental design for a stocking, as shown.

SAM SWANSON.
